UNITED STATES PATENT OFFICE.

RALPH R. RICHARDSON, OF CHICAGO, ILLINOIS.

FOLDING PAPER BOX.

1,114,040.

Specification of Letters Patent.

Patented Oct. 20, 1914.

Application filed May 8, 1912. Serial No. 695,942.

To all whom it may concern:

Be it known that I, RALPH R. RICHARDSON, a citizen of the United States, and a resident of Chicago, county of Cook, and 5 State of Illinois, have invented certain new and useful Improvements in Folding Paper Boxes, of which the following is a full, clear, and exact description.

The invention relates to folding paper 10 boxes and seeks to provide a simple, strong construction which can be economically manufactured and which can be shipped in collapsed or knock-down form.

The invention consists in the features of 15 improvement hereinafter set forth, illustrated in the preferred forms in the accompanying drawing and more particularly pointed out in the appended claims.

In the drawings, Figure 1 is a view of the 20 blank from which the improved box is formed. Fig. 2 is a perspective view illustrating the manner of folding the parts of the box. Fig. 3 is a perspective view of the 25 complete box with the cover or lid open. Fig. 4 is a cross-section of the complete box with the lid closed. Figs. 5 and 6 are views similar to Figs. 3 and 4, respectively, illustrating the modified form.

The improved box comprises a bottom 30 wall *a*, opposite end walls *b* and *c* and opposite side or front and rear walls *d* and *e*. Scored portions 1 form the vertical corners of the box and connect the opposite side and end walls. The side or rear wall *e* is provided at its end with an integral folding tab or flap 2, which is connected thereto by one of the vertical scores 1. The opposite end walls are provided at their upper and lower edges with integral folding flaps 3 35 and 4 which are connected thereto by horizontal scores 5. The upper end flaps 3 are quite narrow, while the bottom end flaps 4 are of considerable width. In the form shown, the narrow, upper end flaps 3 are 40 provided with scalloped edges. The bottom wall *a* is formed integral with the side or front wall *d* and is connected thereto by the horizontal scored portion 6. The bottom has an integral extension *f* connected 45 to its opposite or rear edge by the horizontal score 7 and the extension *f* is provided with the folding portion *g* connected thereto by a horizontal score 8. In the preferred form 50 of the invention shown in Figs. 1 to 4, inclusive, the part *g* forms the cover of the box and is provided at its free edge with an inte-

gral folding flap 10 connected thereto by a horizontal score 11.

After the blank is formed, as shown in Fig. 1, the end wall *b* and the rear wall *d* are folded upon the end wall *c* and front wall *d* and the tab or flap 2 is pasted to the inner face of the edge portion of the end wall *c*. The parts *f* and *g* can then be folded upwardly about the scored line 7 and the box shipped in collapsed condition. In folding the box for use, the side and end walls are separated and the flaps 3 and 4 folded inwardly, as shown in Fig. 2. The bottom *a* is then folded upwardly against the bottom end flaps 4 and the extension *f* and portion *g* thereon are turned up and are passed between the rear wall *e* and the inturned end flaps 3 and 4. To facilitate the passage of the extension *f*, the part *g* 70 and the flap 10 between the rear wall *e* and the flaps 4, the rear edges 12 of the latter are preferably inclined or cut away, as shown. The end flaps 3 and 4 hold the extension *f* snugly against the inner face of 75 the side or rear wall *e* and the folding portion *g* overlaps the upper end flaps 3, so that the extension *f* and folding bottom *a* are securely held in position.

In the preferred form shown in Figs. 1 80 to 4, inclusive, the folding portion *g* forms the cover of the box and the flap 10 at its outer edge is adapted to be inserted between the forward edges of the upper end flaps 3 and the front *d* of the box to hold the cover 85 closed, as shown in Fig. 4. To facilitate opening the box, the upper edge of the front wall is preferably provided with a notch 13.

The form shown in Figs. 5 and 6 is similar to that shown in Figs. 1 to 4, inclusive, 90 except that the folding portion *g'* at the upper end of the extension *f* is quite narrow and, in the form shown, its forward edge is scalloped. This portion *g'* overlaps the upper end flaps 3 and holds the extension *f* and folding bottom *a* in position. In this form of the invention the cover *h* 95 is connected to the upper edge of the rear wall *e* and is preferably formed integral therewith. Like the cover portion *g* of the form shown in Figs. 1 to 4, inclusive, the cover *h* is provided with a flap 10 at its outer edge arranged to be inserted between the front wall and the upper end flaps 3.

The construction can be economically 110 manufactured and shipped in collapsed form. When the parts are opened and folded, as

described, a strong, rigid covered box is provided.

It should be noted that the folding bottom cannot be pushed into the box because it overlaps the lower flaps 4 of the end walls and is held against being depressed by the inturned portion of the extension *f* which overlaps the upper flaps 3 of the end walls. In the preferred form, as shown, the flaps 4 extend inwardly to a point substantially midway between the end walls, so that a strong, double bottom is provided for the box.

It is obvious that changes may be made in the details set forth without departure from the essentials of the invention as defined in the claims.

I claim as my invention:—

1. A folding paper box comprising connected side and end walls, the opposite end walls having inturned flaps at their upper and lower edges, and a folding bottom connected to the lower edge of one of said side walls and overlapping said lower end flaps

and having an upturned extension arranged between the opposite side wall and said upper and lower end flaps, said extension having an inwardly folded portion overlapping said upper end flaps, substantially as described. 25

2. A folding paper box comprising connected front, end and rear walls, said end walls having inturned flaps at their upper and lower edges, and a folding bottom connected to the lower edge of said front wall 30 and overlapping said lower end flaps and having an upturned extension at its rear edge arranged between said rear wall and said upper and lower end flaps, said extension having an inwardly folded portion forming 35 a cover for the box and arranged to overlap said upper end flaps, substantially as described. 40
